UNITED STATES PATENT OFFICE.

DAVID KARGER, OF MILWAUKEE, WISCONSIN.

DESIGN FOR A KNITTED CAP.

Application filed January 14, 1922. Serial No. 194. Term of patent 3½ years.

To all whom it may concern:

Be it known that I, DAVID KARGER, a citizen of the United States, residing at Milwaukee, in the county of Milwaukee and State of Wisconsin, have invented a new, original, and ornamental Design for a Knitted Cap, of which the following is a specification, reference being had to the accompanying drawing, forming part thereof.

I claim:—

The ornamental design for a knitted cap, as shown.

DAVID KARGER.
